signors to Fargo Mfg. Company, Inc., Pough-
keepsie, N. Y., a corporation of New York

Application April 2, 1948, Serial No. 145,498

Term of patent 7 years

(Cl. D26—1)

To all whom it may concern:

Be it known that we, Stephen P. Becker, Ray-
mond B. Schoonmaker, and Henry R. Wengen,
all of whom are citizens of the United States,
residing at Poughkeepsie, in the county of
Dutchess and State of New York, have invented
a new, original, and ornamental Design for Cable
Dead-End Gripping Device, of which the follow-
ing is a specification, reference being had to the
accompanying drawing, forming a part thereof,
wherein:

Fig. 1 is a top plan view of a cable dead-end
gripping device embodying our new design;

Fig. 2 is a slide elevation thereof;

Fig. 3 is an end elevation thereof; and

Fig. 4 is a bottom plan view thereof.

We claim:

The ornamental design for a cable dead-end
gripping device, substantially as shown.

STEPHEN P. BECKER.

RAYMON B. SCHOONMAKER.
